UNITED STATES PATENT OFFICE.

LUELLA HAYMOND, OF SALT LAKE CITY, UTAH.

POLYGONAL DEVICE FOR ABDOMINAL RUPTURE.

Application filed March 14, 1927. Serial No. 175,352.

The rupture support is composed of flexible material such as rubber, which is 5 inches broad at upper edge, $3\frac{1}{2}$ inches wide at lower edge and $4\frac{1}{2}$ inches deep. It is 5 made polygonal in shape encircled with a rounding edge or rim.

The following is a description of my invention, an embodiment of which is illustrated in the annexed drawing; wherein

10 Fig. 1 shows the support in perspective.

Fig. 2 is a similar view of one polygonal frame.

Fig. 3 is a vertical section through the center of frame.

15 No. 1—A solid parallelogram compress, size $2 \times 2\frac{1}{2}$ " and $\frac{3}{4}$ " thick in the center sloping to the joining standards, being convex on either side, which are joined to the rounding edge of the device by three flexible supports at the top edge and three similar supports at the bottom edge and two similar ones on either end of the compress which forms a slanting flexible joining to the rounding edge or rim of the support.

20 No. 2—Polygonal shaped device $4\frac{1}{2}$ " by 5" in size with rounded edges or outer rim $\frac{1}{2}$ " in thickness, being joined to compress by flat flexible standards described by No. 3.

25 No. 3—Are flat flexible standards connecting the center compress with the rounding

edge of the paragonal support. These standards are $\frac{3}{16}$ " thick by $\frac{5}{16}$ " broad with three at the top and three at the bottom edges and two on either side of compress, which are spaced in a convenient manner to 35 strengthen and to give a yielding support to the compress.

No. 4—A connecting belt.

No. 5—A $\frac{3}{4}$ " wide elastic leg strap.

No. 6—A one inch belt for around waist. 40

No. 7—Adjusting clasp.

No. 8—Buckles.

No. 9—Stitching.

Figure 3—Is a key to the form.

No. 1—Thickness of compress being $\frac{3}{4}$ " 45 convex and sloping to the connecting standards.

No. 2—Is rim or edge of polygonal device or appliance.

No. 3—Joining standards. 50

What I claim as my invention is:—

In an abdominal support for hernia, a flexible device comprising a seven sided frame with necessary apertures to admit adjustable straps attached thereto; a compress 55 held in a central position by said straps, and means for fastening the support around the body and to the legs of the wearer.

LUELLA HAYMOND.
